UNITED STATES PATENT OFFICE.

JOSEPH COOK, OF AKRON, OHIO, ASSIGNOR OF ONE-HALF TO THE AKRON STONEWARE COMPANY, OF SAME PLACE.

JUG.

SPECIFICATION forming part of Letters Patent No. 252,649, dated January 24, 1882.

Application filed October 13, 1881. (No model.)

To all whom it may concern:

Be it known that I, JOSEPH COOK, of Akron, in the county of Summit and State of Ohio, have invented a new and useful Improvement 5 in Jugs, of which the following is a specification.

Earthenware jugs have heretofore been almost entirely constructed by hand with a tapering top and with a handle of earthenware 10 on one side or across the top. The disadvantages of such jugs are that the employment of skilled labor is necessary for their production, thereby rendering them expensive. Their peculiar shape prevents their being set in the kiln in stands—*i. e.*, one on another—in burning, which also lessens their capacity with reference to the space they occupy; prevents their 15 being packed close for transportation, thereby rendering them practically useless as packages for shipping, while the handle affords at best an unwieldy and awkward means for handling.

The object of my invention is to obviate these difficulties by the production of a jug which may be formed in molds, may be burned 20 in stands in the kiln, and which, when complete, shall have greater capacity in proportion to the space occupied by it than the jugs in common use; be easily handled and closely packed for transportation. I attain these objects by constructing the jug in the form shown 25 in the accompanying drawings, of which—

Figure 1 is a perspective view, and Fig. 2 a vertical central section.

The jug A consists of a hollow cylinder with 30 sides approximately parallel, the bottom and top being substantially planes and at right angles with the sides. From the top project the mouth B, vent C, and two lugs, D D, in which is inserted a bail, E. The top of the mouth B, 35 vent C, and two lugs, D D, are in the same

plane and parallel to the bottom. The object of placing the lugs, vent, and mouth in one plane is that they may afford a support for another jug to be placed thereon in the kiln for burning or in packing for transportation; but 45 in some instances it is desirable to omit the vent C, in which event its place should be filled by a lug similarly situated and of like height to furnish support for the superimposed jug.

By means familiar to those versed in the art 50 of pottery, the body and top of jugs of this form can be readily made entire, inverted in molds, and the bottoms subsequently placed thereon.

The mouth B, vent C, and lugs D D furnish 55 a support upon which other jugs may be placed either in the kiln or in shipping, while the bail E affords a convenient means for handling.

I claim as my invention—

1. A jug having on its top a mouth or nozzle and two or more lugs, the tops of the mouth and lugs being in a plane parallel to the bottom, substantially as and for the purpose hereinbefore set forth.

2. A jug having at its top a mouth, a vent, 65 and two lugs, the tops of said mouth, vent, and lugs being in the same plane and parallel to the bottom of the jug, substantially as shown, and for the purpose specified.

3. A jug provided upon its top with projecting lugs or bosses the tops of which are in a plane parallel to the bottom, substantially as shown, for the purpose specified.

In testimony that I claim the foregoing I have hereunto set my hand this 3d day of October, A. D. 1881.

JOSEPH COOK.
